UNITED STATES PATENT OFFICE.

JAMES M. ALLEN, OF THERMOPOLIS, WYOMING.

LIFTING DEVICE.

1,368,534.

Specification of Letters Patent.

Patented Feb. 15, 1921.

Application filed May 10, 1920. Serial No. 380,231.

To all whom it may concern:

Be it known that I, JAMES M. ALLEN, a citizen of the United States, residing at Thermopolis, in the county of Hot Springs 5 and State of Wyoming, have invented a new and useful Lifting Device, of which the following is a specification.

This invention relates to lifting devices, and it is the primary object of the invention 10 to provide a portable device of this character which may be readily and easily set up to accomplish the lifting result.

A further object of the invention is to provide a device of this character constructed so that the weight of the article 15 being lifted, will cause the lift proper to be held in a rigid position during the lifting operation.

A still further object of the invention is 20 to provide a lift which may be operated and controlled by a single person, and to enable the person to position carpet or other floor coverings under the article being lifted.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

Referring to the drawing:—

35 Figure 1 illustrates a side elevational view of the lift.

Fig. 2 illustrates a plan view of the same, and

Fig. 3 illustrates a front elevational view 40 showing the lift as applied to a range.

Referring to the drawing in detail, the lift comprises an upper section including spaced arms 5 which are formed preferably of relatively rigid material having the converging arms 6 formed adjacent one end thereof, which arms terminate in offset portions 7, the extreme ends thereof being bolted together by means of the bolts 8 and 10.

50 The bolt 10 which connects the arm 6 also forms a pivot pin for the bell crank lever 11, which has its upper end connected with the operating lever 9 by means of the connecting arms 12, that have pivotal connection with the lever 9 through the medium

of the bolt 13, so that movement of the operating lever 9 produces a relative movement of the arms 12 and the bell crank lever 11.

One arm of the bell crank lever 11 is 60 apertured as at 14 to receive one of the links of the chain 15 which has connection with the lifting chains 16 arranged to cross each other so that the free ends thereof, may be moved to positions in spaced relation with 65 each other, and be connected with an article, at various points thereof to permit the article being lifted to be properly balanced, facilitating the lifting operation.

Disposed on the free ends of the lifting 70 chains 16, are the hook members 17 which are of structures to permit the same to be easily positioned over the article to be lifted in a manner to prevent slipping of the article with relation to the hook members. 75

A yoke indicated at 21 has connection with the arm 6, by means of the bolt 8, the bolt 8' which also has connection with the yoke provides a pivot pin for the upper end of the supporting leg 18 which has its upper end 80 curved as at 19 and positioned between the extreme ends of the arms 6, adjacent the offset portion 7 thereof, and as shown the opposite end of this supporting leg 18, is pointed as at 20 so that the weight of the 85 article being lifted will force the pointed extremity 20 into the floor surface on which the support is positioned, and since this supporting leg 18 is positioned at an angle with relation to the horizontal position of the 90 arms 5, it will be seen that the outer ends of the arms 5, are forced into close engagement with the wall with which the same are associated, during the lifting operation.

In the drawing, the device forming the 95 subject matter of the present invention is shown as employed for lifting a range, to enable a floor covering to be positioned thereunder, and in this showing the arms 5 have their free ends engaging the walls adjacent to the stove, the lever 9 is in a position to be moved downwardly with the result that the arm of the bell crank lever 11, which carries the aperture 14, moves upwardly, carrying therewith the lifting chains 105 16 which in turn have connection with the upper flange of the range. The floor covering may now be rolled under the stove by the person operating the lift, whereupon the operating lever 9 is now moved to the 110

position as indicated by Fig. 1 of the drawing, and the range again moves downwardly where the same rests on the floor covering.

It might be further stated that as the lever 9 is moved downwardly, to accomplish the lifting operation, the arms are forced into engagement with the wall adjacent to the stove, under the weight of the stove being lifted, to prevent movement of the arms 5.

10 Having thus described the invention, what I claim as new is:—

1. In a lift, a pair of spaced arms, said arms having portions thereof converging and secured together, an operating lever pivotally supported between the arms, a bell crank lever pivotally supported between the arms, means having connection with the bell crank lever for securing the device to an article to be lifted, a supporting leg, and 15 means for connecting the bell crank lever and operating lever to cause the bell crank lever to rock and move the means connected therewith, vertically.

2. In a lift, a pair of spaced arms, an operating lever having pivotal connection with the spaced arms adjacent one end thereof, a bell crank lever pivotally supported between the arms, and pairs of arms pivotally con- 20

necting the bell crank lever and operating lever, lifting chains having connection with the bell crank lever, said lifting chains adapted to move vertically when the operating lever is moved in one direction, and a supporting leg having pivotal connection with the arm. 30

3. In a lift, a pair of spaced arms, an operating lever having pivotal connection between the arms, a bell crank lever pivotally connected with the arms, means for connecting the bell crank lever and operating lever, 35 whereby movement of the operating lever produces a relative movement of the bell crank lever, lifting chains having connection with the bell crank lever to move therewith, and a supporting leg having connection with the arms, the supporting leg having a pointed extremity adapted to pierce the floor surface on which the lift is positioned. 40

In testimony that I claim the foregoing as my own, I have hereto affixed my signature 45 in the presence of two witnesses.

JAMES M. ALLEN.
